ABSTRACT OF THE DISCLOSURE

Compounds comprising 3,5-disubstituted-1,2,4-oxadiazoles with one of the substituents being 5-nitro-2-furyl. The compounds are useful as antibacterial, anthelmintic, and anti-trichomonas agents.

SUMMARY

This invention relates to compounds of the formula

In this formula, when R_1 is 5-nitro-2-furyl, R_2 represents diloweralkylaminoloweralkyl, monoloweralkylaminoloweralkyl, cycloloweralkylaminoloweralkyl, morphilinoloweralkyl, azidoloweralkyl, benzylaminoloweralkyl, thiuronium loweralkyl, hydroxyloweralkyl, aminoloweralkyl, cycloaminoloweralkyl, acylaminoloweralkyl, N-loweracylamino-N-cycloloweralkylaminoloweralkyl, N-acyl-N-loweralkylaminoloweralkyl, acylthioloweralkyl, hydroxyloweralkylaminoloweralkyl, bis(hydroxyloweralkyl)aminoloweralkyl, polyhydroxyloweralkylaminoloweralkyl, phenylaminoloweralkyl, phenylalkylaminoloweralkyl, pyridinium loweralkyl, hexamethylene tetrammonium loweralkyl, and loweracyloxyloweralkyl.

Likewise, when R_2 is 5-nitro-2-furyl, R_1 may be any of the enumerated radicals except 5-nitro-2-furyl. The term "loweralkyl" includes the straight and branched alkyl radicals containing from 1-5 carbon atoms. It is also intended to include the non-toxic salts thereof such as the hydrochloride, hydrobromide, sulfate, and quaternary ammonium salts such as, for example, methyl bromide, methyl iodide, benzyl chloride, and methyl sulfate.

More particularly, the compounds of the present invention have the formulas

(B)

(C)

and

wherein R in these and succeeding formulas may be any of the previously enumerated radicals except 5-nitro-2-furyl.

2

These compounds are useful as antibacterial and anti-fungal agents and can be employed as active toxic constituents or disinfectant compositions for the control of microorganisms such as *Salmonella typhimurium*, *Proteus vulgaris*, *Escherichia coli*, *Staphylococcus aureus*, *Chaetomium globosum*, and *Alternaria*. In such use, the compounds are dispersed on an inert solid or in a liquid such as water and applied as a dust or spray. In a typical application, the compound wherein R of Formula C is hydroxymethyl completely inhibited the growth of the above-named microorganisms when employed as an aqueous composition in a concentration of 100 parts per million. Additionally, these compounds are useful as anthelmintic agents when administered intraperitoneally to mice infected with *Schistosomiasis mansoni*. In another typical application, the compounds are effective against *Trichomonas vaginalis* in concentrations of 10 parts per million when applied topically.

DETAILED DESCRIPTION

20 The new compounds can be readily prepared by the following method. A compound of the Formula B or C where R is halomethyl (the preparation of which is hereinafter described) is dissolved in an appropriate solvent such as benzene, toluene, acetonitrile, chloroform, or ethanol, and an appropriate nucleophile is added and refluxed. (A few milliliters of *N,N*-dimethylformamide may be added to assist displacement.) After several hours of refluxing, the solution is cooled; and if a hydrohalide salt of the nucleophile has been formed in the reaction, it is filtered. Upon concentration of the filtrate, the product separates either as a solid or a viscous oil. The compound can be converted to a salt if this is necessary for a solid product. Purification is obtained by recrystallization from a solvent such as ethanol, isopropanol, *n*-butanol, or acetonitrile, among others.

25 In the special case where R is Formula B or C is hydroxymethyl, the acetoxy compound obtained in the reaction described above is treated with ethanolic hydrochloric acid under reflux. The product crystallizes from the reaction mixture and is purified by recrystallization.

30 The compounds of Formula B wherein R is halomethyl (chloro or bromo) and which are the starting materials for the preparation of the compounds of the present invention can be readily prepared by heating at or above the melting point a compound of the formula

35 wherein R is halomethyl, in the absence or presence of a solvent to liberate water and effect ring closure. The preparation of compounds of Formula D will hereinafter be described in detail and is fully described in U.S. Pat. No. 3,272,828. The compound thus formed, if a solid, is then crystallized from a suitable solvent such as ethanol, nitro-methane, or acetonitrile. If the compound is a liquid, it is isolated by distillation under reduced pressure. If desired, equimolar amounts of an R -substituted amidoxime, where R is halomethyl, preferably chloro, and 5-nitro-2-furyl chloride or bromide can be refluxed in an inert solvent such as acetone, toluene, xylene, dimethylformamide, or benzene in the presence of a hydrohalide acceptor such as pyridine, potassium carbonate, or triethylamine or in acetic acid without acid acceptor to form the intermediate compound designated in Formula D above in situ and without actually isolating said intermediate continuing the reaction at reflux temperature to close the ring. The reaction mixture is then concentrated and the residue recrystallized or distilled to obtain the desired oxadiazole.

40 Likewise, the compounds of Formula C wherein R is

halomethyl can be readily prepared by heating at or above the melting point a compound of the formula

in the absence or presence of a solvent to liberate water and effect ring closure. The preparation of compounds of Formula E will hereinafter be described in detail and is fully described in U.S. Pat. No. 3,272,833. The compound thus formed is then crystallized from a suitable solvent such as ethanol, nitromethane, or acetonitrile. If desired, equimolar amounts of 5-nitro-2-furylamidoxime and a compound of the formula RCOX, where R is halomethyl, preferably chloro, and wherein X is a halogen, preferably chlorine or bromine, may be refluxed in an inert solvent such as toluene, xylene, dimethylformamide, or benzene in the presence of a hydrohalide acceptor such as pyridine, potassium carbonate, or triethylamine or in acetic acid without acid acceptor to form the intermediate compound designated in Formula E above *in situ* and without actually isolating said intermediate continuing the reaction at reflux temperature to close the ring. The reaction mixture is then concentrated and the residue recrystallized to obtain the desired oxadiazole as a crystalline solid. Alternatively, an excess of the compound RCOX can be employed as the solvent.

Another method which may be employed is the ring closing of an O-substituted amidoxime, represented by the formula

in which R_1 and R_2 may be any of the previously enumerated radicals with the proviso that both R_1 and R_2 cannot be 5-nitro-2-furyl. When R_1 or R_2 represents dialkylamino-loweralkyl, acylaminoalkyl, or acylthioloweralkyl, this method is more convenient than the previously-described method.

This ring closure can be readily carried out by heating the starting material (the preparation of which is herein-after described) at or above its melting point or in the presence of a solvent to liberate water. Solvents such as n-butanol, benzene, toluene, or N,N-dimethylformamide are suitable for the procedure. Upon cooling the melt or the solvent, the desired product crystallizes. Purification is achieved by recrystallization from ethanol, butanol, ethyl acetate, or other suitable solvents.

The compounds of Formula F may be made by the known acid halide procedure as disclosed in U.S. Pat. Nos. 3,272,828 and 3,272,833. Alternatively, these compounds can be made in accordance with the following scheme:

The reaction is run in solvents such as acetonitrile, dimethylformamide, 1,2-dimethoxyethane, chloroform, ether, and the like. Equimolar quantities of the acid and the amidoxime are employed in the presence of 1.0 to 1.25 moles of a condensing agent such as dicyclohexylcarbodiimide, at ambient temperatures.

If desired, equimolar quantities of ethylchloroformate and an acid acceptor, i.e., triethylamine, pyridine, and the like, may be employed to form the intermediate mixed anhydride of the acid which acylates the amidoxime. This reaction is run at 0°-5° C. initially, followed by ambient temperatures. Of course, the proper reactants must be selected in order to obtain the desired starting material of Formula F.

The examples which follow are presented as illustrations rather than limitations of the invention.

EXAMPLE 1

- 5 3-[(diethylamino)methyl]-5-(5-nitro-2-furyl)-1,2,4-oxadiazole

To 4.5 ml. of anhydrous diethylamine is added 2.58 g. (0.01125 mole) of 3-(chloromethyl)-5-(5-nitro-2-furyl)-2,4-oxadiazole with stirring at room temperature. After solution is effected, the reaction mixture is heated on a steam bath for 0.5 hours. The dark reaction mixture which forms is filtered and the residue washed with anhydrous benzene. The benzene filtrates are concentrated to dryness under vacuo and the residual oil taken up in anhydrous ether, the solution heated with decolorizing charcoal. After filtration of the latter mixture, the ether filtrates are treated with ethereal HCl. The solid which precipitates is filtered and dried, weight 2.0 g. (59%), M.P. 59° dec. The product is purified by crystallization from absolute alcohol. The pure product melts at 170°-171°.

Analysis.—Calc. for $C_{11}H_{15}ClN_4O_4$ (percent): C, 43.64; 25 H, 5.01; N, 18.54; Cl, 11.73. Found (percent): C, 43.67; H, 5.02; N, 18.66; Cl, 11.77.

EXAMPLE 2

- 30 2-[[5-(5-nitro-2-furyl)-1,2,4-oxadiazol-3-yl]methyl]-2-thiopseudourea

To a solution of 4.0 g. (.01741 mole) of 3-(chloromethyl-
yl)-5-(5-nitro-2-furyl)-1,2,4-oxadiazole in absolute etha-
nol is added 1.65 g. (0.0218 mole) of thiourea. The mix-
ture is heated at reflux for 1 hours. After one-half hour
the product separated. The precipitated solid is filtered
and washed with absolute alcohol. The residue after dry-
ing weighs 4.70 g. (88.4%). M.P. 220° dec.

Analysis.—Calc. for $C_8H_8ClN_5O_4S$: (percent): C, 31.43; H, 2.64; N, 22.91. Found (percent): C, 31.62; H, 2.71; N, 22.76.

EXAMPLE 3

- ### 5-(5-nitro-2-furyl)-1,2,4-oxadiazole-3-methanol

50 A mixture containing 5.0 g. (0.0218 mole) of 3-(chloromethyl)-5-(5-nitro-2-furyl)-1,2,4-oxadiazole, 1.79 g. (0.0218 mole) of anhydrous sodium acetate, 60 ml. of absolute ethanol, and 4 drops of dimethylformamide is heated at reflux for 24 hours. The reaction mixture is filtered and the filtrate taken to dryness. The oil residue is
 55 mixed with ether and the ether extracts are washed with water. The ether layer is stirred with decolorizing charcoal, filtered, and the resulting pale yellow filtrates dried over magnesium sulfate. After filtering from the drying agent, the ether solution is concentrated to dryness under
 60 vacuo. The oil residue is the crude acetoxy derivative as shown by infrared analysis. Weight 3.80 grams.

The crude oil was taken into solution with 50 ml. of 95% ethanol and 10 ml. of concentrated hydrochloric acid added. The mixture is heated at reflux for 6 hours. The mixture is concentrated under *vacuo*. The resulting oil is triturated with ether, the ether solution washed with water until no longer acidic and then dried over anhydrous magnesium sulfate. After filtering the drying agent, the filtrates when taken to dryness yield 2.31 g. of tacky solid. By taking the oil up in hot toluene and with the use of decolorizing charcoal, the product is obtained as a white solid, M.P. 114°-115°.

Analysis.—Calc. for $C_7H_5N_3O_5$ (percent): C, 39.82; H, 2.39; N, 19.90. Found (percent): C, 39.94; H, 2.33; N, 19.73.

EXAMPLE 4

N-[[5-(5-nitro-2-furyl)-1,2,4-oxadiazol-3-yl]methyl]benzamide

One gram of 0-5 nitro-2-furoyl-N-benzoylaminoacet- 15
amidoxime (M.P. 188°-189°) is heated at 190° under
reduced pressure. After cessation of gas evolution, the
melt is poured into a crystallizing dish. The glass is taken
up in excess 95% alcohol with heat, heated with decolorizing
charcoal and the mixture filtered. The filtrates are
concentrated to 15 ml. and chilled. The product is fil-
tered and washed with cold alcohol. The product after
drying weighed 0.61 g. (64.5%), M.P. 161°-162°.

5

Analysis.—Calc. for $C_{14}H_{10}N_4O_5$ (percent): C, 53.51;
H, 3.21; N, 17.83; O, 25.46. Found (percent): C, 53.47;
H, 3.51; N, 17.86; O, 25.44.

EXAMPLE 5

N-methyl-N-[[5-(5-nitro-2-furyl)-1,2,4-oxadiazol-3-yl]methyl]acetamide

10

13.9 g. (0.049 mole) of O-acylamidoxime is refluxed
in 600 ml. of n-butanol overnight and then concentrated
to an oil. Recrystallization from ethanol gave the product
with a melting point of 119°-121° C. 20

Using methods exemplified in the foregoing examples,
the following compounds, wherein R refers to substitu-
tions in Formula B, were made.

Example	R	M.P. in degrees	Salt	Recrystallization solvent	Analysis			Mol. wt.

EXAMPLE 23

2-[[3-(5-nitro-2-furyl)-1,2,4-oxadiazol-5-yl]methyl]amino]ethanol

R=CH₂NHCH₂CH₂OH in Formula C

4.6 g. of 5-(chloromethyl)-3-(5-nitro-2-furyl)-1,2,4-oxadiazole is dissolved in 100 ml. of benzene containing 5 ml. of N,N-dimethylformamide. 2.4 g. (0.04 mole) of ethanalamine is added in 25 ml. of benzene. The solution is refluxed for 12 hours and then cooled. The ethanalamine hydrochloride is filtered, and the filtrate is concentrated to an oil. The oil is then crystallized from boiling ethanol. M.P. 114°-116° C.

EXAMPLE 24

5-[(dimethylamino)methyl]-3-(5-nitro-2-furyl)-1,2,4-oxadiazole

R=CH₂N(CH₃)₂·HCl in Formula C

4.6 g. (0.02 mole) of 5-chloromethyl-3-(5-nitro-2-furyl)-1,2,4-oxadiazole is dissolved in 100 ml. of benzene containing 5 ml. of dimethylformamide. 1.8 g. (0.02 mole) of dimethylamine is added to the benzene solution and refluxed overnight. The hydrochloride of dimethylamine is filtered and the filtrate is concentrated to an oil. The oil is dissolved in 20 ml. of ether and the solution is washed with water and dried for 30 minutes over MgSO₄. Ethereal HCl is added. The hydrochloride of the product precipitates as a white solid. Yield of crude product is 86.6%. For analysis, the compound is recrystallized from boiling ethanol. M.P., 210°-215° C.

EXAMPLE 25

4-[[3-(5-nitro-2-furyl)-1,2,4-oxadiazol-5-yl]methyl]morpholine

4.6 g. of 5-chloromethyl-3-(5-nitro-2-furyl)-1,2,4-oxadiazole was dissolved in 100 ml. of benzene containing 1 ml. of dimethylformamide. 3.5 g. of morpholine is added and refluxed for two hours.

The morpholine hydrochloride is filtered and the benzene solution is concentrated to an oil. The oil crystallizes from ethanol. Yield is 68%. For analysis, the material is recrystallized from ethanol. M.P., 125°-126° C. (dec.).

EXAMPLE 26

Diethylmethyl[[3-(5-nitro-2-furyl)-1,2,4-oxadiazol-5-yl]methyl]ammonium iodide

10.6 g. of 5-diethylaminomethyl-3-(5-nitro-2-furyl)-1,2,4-oxadiazole is dissolved in 50 ml. of ethanol. 10 g. of methyl iodide is added and the solution is refluxed for 1 hour. The solution is then cooled until crystals form. The final compound is crystallized from ethanol. Recovery is 10 g. M.P., 158°-160° C. (dec.).

EXAMPLE 27

3-(5-nitro-2-furyl)-1,2,4-oxadiazole-5-methanol

R=CH₂OH in Formula C

4.6 g. of 5-chloromethyl-3-(5-nitro-2-furyl)-1,2,4-oxadiazole and 1.7 g. of sodium acetate in 100 ml. of ethanol are refluxed for 72 hours. The resulting solution is filtered, and 10 ml. of concentrated hydrochloric acid is added. The solution is refluxed overnight and then filtered. Upon concentration, a white solid crystallizes. A recrystallization from boiling ethanol raises the melting point to 132°-134° C.

EXAMPLE 28

3-(5-nitro-2-furyl)-5-methylamino-1,2,4-oxadiazole

R=CH₂NH₂·HCl in Formula C

9.2 g. of 3-(5-nitro-2-furyl)-5-chloromethyl-1,2,4-oxadiazole and 5.6 grams of hexamethylene tetraamine were refluxed for 2 hours. The white quaternary salt is filtered from the solution. The solid is suspended in 40 ml. of ethanol containing 15 ml. of concentrated hydrochloric acid and allowed to stand for 48 hours at room temperature. The solution is then neutralized with sodium carbonate and extracted three times with ether. The ether is dried and ethereal hydrochloride is added. The hydrochloride precipitates as the product. Yield is 1.0 g., M.P. 200°-202° C.

EXAMPLE 29

N-[[3-(5-nitro-2-furyl)-1,2,4-oxadiazol-5-yl]methyl]acetamide

36.9 g. (0.1365 mole) of 5-nitro-2-furamidoxime O-acetate is heated above melting point for 10 minutes. A dark oil solidifies to black solid upon standing, producing 32.5 g. (94.2%) of the product. Recrystallization from absolute ethanol gave 23.8 g. (68%) of product. M.P., 156°-158° C.

EXAMPLE 30

5-(aminomethyl)-3-(5-nitro-2-furyl)-1,2,4-oxadiazole

R=CH₂NH₂ in Formula C

Neutralization of a small amount of the HCl salt of the compound of Example 28 with an equivalent amount of NaHCO₃ solution gave the free base. Recrystallization from i-propanol gave product, melting point—88°-89° C.

EXAMPLE 31

1-[[3-(5-nitro-2-furyl)-1,2,4-oxadiazol-5-yl]methyl]pyridinium chloride

4.6 g. (0.02 mole) of 5-chloromethyl-3-(5-nitro-2-furyl)-1,2,4-oxadiazole is dissolved in 25 ml. of acetonitrile and 2.0 g. of pyridine is added. The solution is heated at 55° C. for 2 hours, whereupon 3.1 g. of product is obtained. The product is recrystallized from ethanol for analysis. M.P., 195°-197° C. (dec.).

Using methods exemplified in the foregoing examples, the following compounds, wherein R refers to substitutions in Formula C, were made.

Example	R	M.P. in degrees	Salt	Recrystallization solvent	Analysis			Mol. wt.
					Calculated		Found

¹ Dec.² Free base.

The synthesis of the Formula B or C where R is azidoloweralkyl may be accomplished by reacting the appropriate halomethyl derivative, previously described, with a slight excess of sodium azide (a small amount of dimethylformamide or sodium iodide may be added to facilitate reaction) in acetonitrile, ethanol, isopropanol, or the like, at reflux for 24-48 hours. Filtration of the reaction mixture followed by concentration and purification yields the desired product.

What is claimed is:

1. A compound of the formula:

wherein when one of R₁ and R₂ is 5-nitro-2-furyl, the other is a member of the group consisting of diloweralkyl-

aminoloweralkyl, monoloweralkylaminoloweralkyl, cyclohexylaminoloweralkyl, morpholinoloweralkyl, azidoloweralkyl, benzylaminoloweralkyl, thiuronium loweralkyl, hydroxyloweralkyl, aminoloweralkyl, cycloamino-loweralkyl, acylaminoloweralkyl, N-loweracylaminoloweralkyl, N-acyl-N-loweralkylaminoloweralkyl, acylthioloweralkyl, hydroxyloweralkylaminoloweralkyl, bis(hydroxyloweralkyl)aminoloweralkyl, polyhydroxyloweralkylaminoloweralkyl, phenylaminoloweralkyl, pyridinium loweralkyl, hexamethylene tetramonium loweralkyl, and loweracyloxyloweralkyl; and non-toxic salts thereof, "acyl" is a member of the group consisting of the acetyl, propionyl and benzoyl radicals, and "polyhydroxy" including radicals containing from one to three hydroxyl groups.

2. A compound as claimed in claim 1 wherein R₁ is 5-nitro-2-furyl and R₂ is a member of the group consist-

13

ing of diloweralkylaminoloweralkyl, monoloweralkylaminoloweralkyl, cyclohexylaminoloweralkyl, morpholinoloweralkyl, azidoloweralkyl, benzylaminoloweralkyl, thiuronium loweralkyl, hydroxyloweralkyl, aminoloweralkyl, cycloaminoloweralkyl, acylaminoloweralkyl, N-lower-acylaminino-N-cyclohexylaminoloweralkyl, N-acyl-N-loweralkylaminoloweralkyl, acylthioloweralkyl, hydroxyloweralkylaminoloweralkyl, bis(hydroxyloweralkyl)aminoloweralkyl, polyhydroxyloweralkylaminoloweralkyl, phenylaminoloweralkyl, phenylalkylaminoloweralkyl, pyridinium loweralkyl, hexamethylene tetrammonium loweralkyl, and loweracyloxyloweralkyl, "acyl" is a member of the group consisting of the acetyl, propionyl and benzoyl radicals, and "polyhydroxy" including radicals containing from one to three hydroxyl groups.

3. A compound as claimed in claim 1 wherein when R₁ is 5-nitro-2-furyl, R₂ is morpholinoloweralkyl; and when R₂ is 5-nitro-2-furyl, R₁ is morpholinoloweralkyl.

4. A compound as claimed in claim 2 wherein R₂ is hydroxyloweralkylaminoloweralkyl.

5. A compound as claimed in claim 2 wherein R₂ is pyridinium loweralkyl.

6. A compound as claimed in claim 2 wherein R₂ is monoloweralkylaminoloweralkyl.

7. A compound as claimed in claim 2 wherein R₂ is acylthioloweralkyl, "acyl" is a member of the group consisting of the acetyl, propionyl and benzoyl radicals.

8. A compound as claimed in claim 1 wherein R₂ is 5-nitro-2-furyl and R₁ is a member of the group consisting of diloweralkylaminoloweralkyl, monoloweralkylaminoloweralkyl, cyclohexylaminoloweralkyl, morpholinoloweralkyl, azidoloweralkyl, benzylaminoloweralkyl, thiuronium loweralkyl, hydroxyloweralkyl, aminoloweralkyl, cycloaminoloweralkyl, acylaminoloweralkyl, N-lower-acylaminino-N-cyclohexylaminoloweralkyl, acylthioloweralkyl, hydroxyloweralkylaminoloweralkyl, bis(hydroxyloweralkyl)aminoloweralkyl, polyhydroxyloweralkylaminoloweralkyl, phenylaminoloweralkyl, phenylalkylaminoloweralkyl, pyridinium loweralkyl, hexamethylene tetrammonium loweralkyl, and loweracyloxyloweralkyl, "acyl" is a member of the group consisting of the acetyl, propionyl and benzoyl radicals, and "polyhydroxy" including radicals containing from one to three hydroxyl groups.

9. A compound as claimed in claim 8 wherein R₁ is 45 thiuronium loweralkyl.

14

10. A compound of the formula:

wherein when one of R₁ and R₂ is 5-nitro-2-furyl, the other is a member of the group consisting of hydroxyloweralkyl and acylaminoloweralkyl, "acyl" is a member of the group consisting of the acetyl, propionyl and benzoyl radicals.

11. A compound of the formula

wherein R₁ is 5-nitro-2-furyl and R₂ is aminoloweralkyl.

12. A compound of the formula:

wherein R₂ is 5-nitro-2-furyl and R₁ is N-acyl-N-loweralkylaminoloweralkyl, "acyl" is a member of the group consisting of the acetyl, propionyl and benzoyl radicals.
